Carl E. Thommes

UNITED STATES PATENT OFFICE.

MATHIAS C. BUSCH AND CARL E. THOMMES, OF ST. PAUL, MINNESOTA.

COMBINATION TOOL.

Application filed June 29, 1922. Serial No. 571,700.

To all whom it may concern:

Be it known that we, MATHIAS C. BUSCH and CARL E. THOMMES, citizens of the United States, residing at St. Paul, in the county of Ramsey and State of Minnesota, have invented certain new and useful Improvements in a Combination Tool, of which the following is a specification.

This invention relates to a combination wrench, the prime object of which is to provide a tool of this character having several other features adapted to be used in connection with the regular function of a monkey wrench.

15 A further object of the invention is to provide a wrench with a quick-adjusting jaw having means whereby the quick-adjusting jaw may be moved into an inoperative position and the operating handle of 20 the quick-adjusting jaw used as a screwdriver.

A still further object of the invention is to provide a combination tool of the above indicated character, which is simple in construction, durable, efficient for the purpose intended, and one that can be manufactured and placed on the market at a relatively low cost.

These and like objects of the invention 30 will be better understood as the description proceeds and as is specifically pointed out in the appended claims.

Referring to the accompanying drawings which form a part of this specification and 25 which clearly illustrate the construction and operation of our improved tool,

Figure 1 is a side elevation of a combination tool constructed in accordance with our invention;

40 Fig. 2 is a rear elevation of same;

Fig. 3 is a side elevation in section, to better illustrate the construction and operation of the tool;

Fig. 4 is a transverse section taken on line 4—4 of Fig. 3;

Fig. 5 is a side elevation of the stationary jaw;

Fig. 6 is a side elevation of the movable jaw; and

50 Fig. 7 is a fragmentary side elevation, partly in section showing a modified form of tool.

Referring to the accompanying drawing in detail, like characters will be used to designate like parts in the different views.

In the drawings, the numeral 1 indicates

a stationary jaw mounted on one end of a handle 2 and having one edge of the handle as at 3 provided with rack teeth. A movable jaw 4, which is formed in approximately a U-shaped manner as indicated in Fig. 4, is slidable on the handle 2 and has pivotally connected as at 5 an operating handle 6. The free end of the handle 6 tapers to a point as at 7 to provide a screwdriver. The inner edge of the handle 6 is provided with rack teeth 8, which are adapted to engage the rack teeth 3 on the handle 2, for locking the movable jaw 4 at any desired point on the handle 2.

The movable jaw 4 is provided with a longitudinal bore 9, and has positioned therein crosswise of the bore a pin 10, around which is positioned a flap spring 11, one end of the spring engaging the cross-pin 10, while the free end of the spring engages the outside edge of the operating handle 6 as at 13. The spring also engages the movable jaw as indicated at 13. By means of this arrangement the flap spring is guided into and out of the longitudinal bore or slot 9 as desired by the operator of the wrench.

Fig. 7 is a modified form of the invention showing the stationary and adjustable handles 2 and 6 respectively in reversed position to that shown in Fig. 3. A movable jaw 4 is shown herein with the bore 9 formed to receive the spring 11, which has one end thereof bearing against the movable handle 6.

From the foregoing description taken in connection with the accompanying drawing, it can be readily seen that when a new adjustment of the movable jaw relative to the stationary jaw is desired, the operating handle 6 is moved outwardly against tension of the spring 11, thus disengaging the rack teeth 8 of the operating handle from the rack teeth 3 formed on the stationary jaw handle, after which the movable jaw 4 is moved into any desired position on the handle 2 and the operating handle 6 is then allowed to move back into engagement with the rack teeth 3 under the influence of the spring 11, thus firmly locking the movable jaw against accidental movement. When it is desired to use the end of the operating handle 6 as a screw-driver, the spring 11 is moved lengthwise within the bore 9, until the free end of the spring disengages the edge of the operating handle, after which

the operating handle is moved at approximately right angles to the movable jaw 4 and can then be used for a screw-driver or other purpose as may be desired.

5 The stationary jaw 1 is formed with an enlarged end 14, which can be used as a hammer, while the free end of the handle 2 can be used for removing tires from the rim of an automobile wheel.

10 19 In view of the foregoing description of our invention, it is thought that any further explanation as to the construction, operation, and objects of the same are unnecessary.

15 20 While we have shown and described the preferred form of our invention, we realize that various minor changes may be resorted to, without departing from the spirit and scope of the invention as claimed, and therefore we do not wish to limit ourselves to the exact details of construction shown, nor to the combination and arrangement of parts.

What we claim as new and desire to secure by Letters Patent is:

25 1. In a tool of the above indicated character comprising a stationary jaw mounted on one end of a handle, a movable jaw positioned on said handle, an operating handle pivotally connected to said movable jaw, rack teeth formed on the opposing edges of the stationary jaw handle and the operating handle, and means slidably positioned within the movable jaw for forcing the rack teeth of the operating handle into engagement with the teeth of the stationary jaw handle for holding the movable jaw in any desired adjustment.

2. In a tool of the above indicated character comprising a stationary jaw mounted on one end of a handle, a movable jaw, an operating handle pivotally connected to said movable jaw, rack teeth formed on the opposing edges of said stationary jaw handle and operating handle, said movable jaw provided with a longitudinal bore having a flap operating spring slidable therein, said operating spring adapted to engage the outer edge of said operating handle for holding said handle into engagement with the handle of the stationary jaw to hold the movable jaw in any desired position on the handle of the stationary jaw.

3. A tool of the character described comprising a stationary jaw mounted on one end of a handle, a movable jaw having a longitudinal bore formed therein, an adjustable handle pivotally connected to said jaw, rack teeth formed on the opposing edges of the handles, a flap operating spring slidably mounted within said bore, and a cross-pin engaging one end of said spring for guiding the latter, said spring bearing against the outer edge of the adjustable handle for holding the same in engagement with the handle of the stationary jaw for holding the movable jaw in any desired position on the handle of the stationary jaw.

In testimony whereof, we have affixed our signatures in the presence of two witnesses.

MATHIAS C. BUSCH.
CARL E. THOMMES.
